(57) **CLAIM**

The ornamental design for a liquid dispenser, as shown and described.

DESCRIPTION

FIG. 1 is a perspective view showing our new design for a liquid dispenser;

FIG. 2 is a front view thereof;

FIG. 3 is a top view thereof;

FIG. 4 is a bottom view thereof;

FIG. 5 is a rear view thereof;

FIG. 6 is a side view thereof;

FIG. 7 is a perspective view showing the cap, spray bottle and unclaimed cloth in a separated state illustrating use;

FIG. 8 is a perspective view of the spray bottle shown

without the cover for a clear and complete disclosure of the

underlying parts;

FIG. 9 is a front view thereof;

FIG. 10 is a rear view thereof;

FIG. 11 is a bottom view thereof;

FIG. 12 is a front, and rear view of the cover element of

FIGS. 1-7, shown separately for clarity of disclosure;

FIG. 13 is a side view thereof;

FIG. 14 is a top view thereof, the bottom view being similar

except for the slight thickness of the perimeter edge;

FIG. 15 is a front and rear view showing a second embodi-

ment of the cover element, the top and bottom and bottom

views thereof being the same as the first embodiment.

FIG. 16 is a side view thereof.

FIG. 17 is a front and rear view showing a third embodiment

of the cover element, the top and bottom and bottom

views thereof being the same as the first embodiment;

FIG. 18 is a side view thereof;

FIG. 19 is a front and rear view showing a fourth embodi-

ment of the cover element, the top and bottom views thereof

being the same as the first embodiment; and,

FIG. 20 is a side view thereof.

The broken line in FIG. 4 forms no part of the claim, but is

provided to indicate the boundary of the unclaimed region of

the bottom end. The broken lines showing the cloth in FIG.

7 form no part of the claimed design, but are included for the

purpose of illustrating the nature and intended use thereof.
